UNITED STATES PATENT OFFICE.

ROBERT LEVI, OF NEW YORK, N. Y.

DRESS-SHIELD AND PROCESS OF MAKING SAME.

1,272,684.

Specification of Letters Patent.

Patented July 16, 1918.

Application filed May 15, 1916. Serial No. 97,481.

To all whom it may concern:

Be it known that I, ROBERT LEVI, a citizen of the United States, residing in the borough of Manhattan, city, county, and State of New York, have invented certain new and useful Improvements in Dress-Shields and Processes of Making Same, of which the following is a specification.

My invention relates to an improved dress-shield and method of manufacturing the same. Dress-shields as ordinarily made have a binding or braid secured about the outside edges to give finish and to conceal the rough edges of the seams. Such bindings are relatively expensive and are also stiff and uncomfortable for the wearer. They also present the difficulty that it is impossible to have the braid properly match the colors of the lining and outside or cover portions of the shield in most instances. My invention does away with these difficulties by providing a dress-shield in which no braid or binding is used, and a method of making the same, whereby the various members of the shield are so secured together that the rough edges of the seams are in the interior of the construction where they are out of the way, the visible portions of the shield thus presenting a neat appearance, without the use of the braid or binding referred to.

In order that a clearer understanding of my invention may be had, attention is hereby directed to the accompanying drawings forming part of this application and illustrating my improved process and product. In the drawings, Figure 1 represents in face view a pair of cover members secured together, this constituting the first step of the process; Fig. 2 represents in face view the members of the shield secured together as in the second step of the process; Fig. 3 is a vertical cross-section taken on line 3—3 of Fig. 2; Figs. 4, 5 and 6 represent face views of the shield in subsequent stages of construction; Fig. 7 is a face view of the finished shield and Fig. 8 is an enlarged, somewhat diagrammatic cross-section taken on line 8—8 of Fig. 7.

Referring to the drawings, a pair of cover members 1, 1, of shield or crescent shape, are first superposed and stitched together along the line 2 adjacent to the inside or concavely-curved edges 3 of the members. These cover members may be of any suitable material,

such as sateen, or the like, and are placed together as shown in Fig. 1 with their outer or finished sides together. The cover members 1, 1 are then reversed about the seam 2, so that the finished sides of the members will be outside and the rough edges or ridge of the seam inside. 60

The lining members 4, 4, of muslin, or the like, are then laid upon the outside or finished surfaces of members 1, 1 and the moistureproof member 5, of rubber, or the like, is laid upon the opposite or unfinished faces of the cover members 1, 1. Each lining member is then stitched through the adjacent cover member to the moistureproof member along the lines 6, 6, adjacent to the outer or convexly-curved edges of the shield. This stage of the operation is represented in Figs. 2 and 3, in which the shield is shown as being thus secured together and folded about the concavely-curved seam 2, the upper leaf of the shield being folded back in Fig. 2 to show that the moistureproof member 5 is on the inside at this stage of the construction. The upper lining member 4 and the other members of the construction are also shown broken away in part, to show the relative position of the various members. 75

The result of the last operation is to form a pair of pockets, the outer sheet of each being formed by a lining member 4 and the inner sheet being formed of the outer cover 1 and one-half of the moistureproof member 5, the outer cover 1 being next to the lining member 4. Also the rough edges 7 caused by the stitching 6 are on the outside. Accordingly, the next step of the operation consists in turning each pocket inside out, as is shown in Fig. 4. As is shown in this figure, the lining member 4 is still 90 on the outside, but the outside cover 1 now forms the inner surface of each pocket, the moistureproof member 5 now being between the lining 4 and the outer cover 1 of each pocket. Also, the ridge or rough edge of 95 the outside seam formed by the stitching 6 around each pocket is now on the inside of the pocket. 100

The pockets of the shield now being laid one upon the other, that is, the shield being 105 folded along the seam 2, as shown in Figs. 4 and 5, with the lining members 4, 4 at the top and the bottom, respectively, the lining members 4, 4 are now stitched together along the concavely-curved line 8, above the fold 110

of the moistureproof member and adjacent to the concavely-curved or inside edges 9 of the lining members 4.

This having been done, it is only necessary 5 to fold the shield in reverse position, that is, to rotate the two members of the shield through 180° about the concavely-curved line thereof, so that the outside cover members 1 will be outside and the lining members 10 4 will be inside, as is shown in Fig. 6. The seam 8 will now be on the inside, as is shown in Fig. 6. It is now only necessary to iron and smooth the shield to finish the same.

15 The finished shield is illustrated in Fig. 7 and the arrangement of the members thereof is shown somewhat diagrammatically in Fig. 8. The stitching 6' may be added, if desired, as shown in Figs. 7 and 8, to make a 20 more finished appearance.

It will be understood that my invention is not limited strictly to all of the details above described, but that a resemblance of equivalents is included therein.

25 Having now particularly described my invention, what I claim and desire to protect by Letters Patent is as follows:—

1. As a new article of manufacture, a dress-shield comprising a lining, an outside cover, and a moistureproof member extending between the same, said lining, cover and moistureproof member having rough convex edges, and being stitched together adjacent said edges, with the cover and lining meeting at the lines of stitching, at the extreme outside edges of the shield, and having their outer surfaces coextensive at such edges, the lining, cover and moistureproof member being bent back from the stitching to extend 35 40 side by side therefrom to their rough edges, between the lining and the cover, the edges of the seams being concealed between the lining and cover.

2. The process of making a dress-shield, 45 consisting in superposing a pair of shield-shaped cover members and stitching the same along the concavely-curved edge, reversing the members to place the ridge of the same

inside, placing a moistureproof member, folded upon itself along a concavely-curved 50 line, between the cover members, and a pair of lining members upon the outer faces of the cover members, stitching together one leaf of the moistureproof member and the adjacent cover and lining members along 55 the outside or convex edge and similarly stitching together the other leaf of the moistureproof member and the other cover and lining member, turning each pocket thus formed inside out and folding the structure 60 upon itself, along the concavely-curved median line of the moistureproof member, with the cover members superposed and the lining members outside, and stitching the lining members together along the concavely-curved edges thereof, about the fold 65 of the moistureproof member, substantially as set forth.

3. The process of making a dress-shield, 70 consisting in superposing, on a moistureproof member, an outer covering and a pair of lining members on the outer covering, with the curved inside edges of the lining members adapted to overlap, stitching each lining member through the outer covering 75 to the moistureproof member, adjacent the outside convexly curved edges of all of the same, turning each pocket thus formed inside out, to position the moistureproof member and the ridges of the seams between the 80 lining members and the outer covering, folding the structure upon itself along the concavely-curved median line of the moistureproof member, with the lining members outside and the folded outer covering inside, 85 and stitching the lining members together along the curved meeting edges thereof, about the fold of the moistureproof member, substantially as set forth.

This specification signed and witnessed 90 this 12th day of May, 1916.

ROBERT LEVI.
